(57) CLAIM

The ornamental design for a feminine hygiene storage container, as shown and described.

DESCRIPTION

FIG. 1 is a front view of a feminine hygiene storage container showing my new design;

FIG. 2 is a rear view of the feminine hygiene storage container;

FIG. 3 is a right side view of the feminine hygiene storage container;

FIG. 4 is a left side view of the feminine hygiene storage container;

FIG. 5 is a top view of the feminine hygiene storage container;

FIG. 6 is a bottom view of the feminine hygiene storage container;

FIG. 7 is a top front side perspective view of the feminine hygiene storage container with a medial panel in an alternative lowered position; and,

FIG. 8 is a top front side perspective view of the feminine hygiene storage container with a medial panel in an alternative raised position.

The broken lines in FIGS. 7 and 8 depict environmental subject matter that form no part of the claimed design.

1 Claim, 8 Drawing Sheets
